[57] CLAIM

The ornamental design for a wing element for a toy aircraft, as shown and described.

DESCRIPTION

FIG. 1 is a top perspective view of a wing element for a toy aircraft showing my new design;

FIG. 2 is a bottom perspective view thereof;

FIG. 3 is a top plan view thereof;

FIG. 4 is a side elevational view thereof, the side opposite being a mirror image;

FIG. 5 is a front elevational view thereof;

FIG. 6 is a rear elevational view thereof;

FIG. 7 is a bottom plan view thereof.
